THE NORRIS PETERS CO., PHOTO-LITHO., WASHINGTON, D. C.

UNITED STATES PATENT OFFICE.

FRANK J. LUDINGTON, OF WATERBURY, CONNECTICUT.

CIGARETTE-MACHINE.

SPECIFICATION forming part of Letters Patent No. 655,254, dated August 7, 1900.

Application filed March 9, 1899. Serial No. 708,348. (No model.)

To all whom it may concern:

Be it known that I, FRANK J. LUDINGTON, a citizen of the United States, residing at Waterbury, New Haven county, Connecticut, have invented certain new and useful Improvements in Cigarette-Machines, of which the following is a full, clear, and exact description.

My invention relates to machines for making cigarettes, with particular reference to that class known in the art as "continuous" machines.

In the present machine the tobacco instead of being molded into a stick or rod of definite shape and dimensions before being supplied with an envelop or wrapper is delivered while in a perfectly-loose state directly upon the paper which finally becomes the cigarette-wrapper. The paper is of the form of a continuous strip and rests upon an endless traveling tape or band of suitable material adapted to carry the paper along. A device for feeding tobacco in a continuous and uniform shower is employed, and the discharge-spout thereof is so located as to direct the tobacco fibers between a pair of substantially-parallel guides forming the side pieces of a groove or channel, at the bottom of which is the traveling wrapper-strip. The tobacco falling within said groove or channel forms a loose, flaky, but rather bulky mass, which is advanced by the wrapper-strip and in passing subjected to the action of suitable compressing and shaping devices hereinafter specifically described. Preferably these compressing and shaping devices are so constructed and operate in such manner that the tobacco is first compressed in a perpendicular direction and then in lateral directions from opposite sides, so that a tobacco rod of substantially-square cross-section is formed upon the surface of the traveling wrapper-strip, the wrapper-strip meanwhile maintaining a flat position and having its edges extending out from opposite sides of said rod. Advancing farther the square tobacco rod is converted into a rod of cylindrical, elliptical, or other curved cross-section, and the sides of the wrapper-strip are gradually raised and formed into an open trough, whose sides are substantially parallel and whose bottom is semi-circular, the tobacco rod lying within and

fitting said bottom. The tobacco rod being completed and partially enveloped by the wrapper-strip passes on to a suitable folding device, whereby the upstanding sides of the wrapper-strip or trough aforesaid are turned down over the tobacco. One of the sides is turned down ahead of the other, while the remaining upstanding edge receives a supply of paste along the inner edge thereof, whereupon the pasted edge also is turned down and lapped over and pressed against the edge of the side first mentioned. The completed cigarette rod then emerges from the folding device ready to be cut up into suitable short sections.

In the accompanying drawings, showing the preferred embodiment of my invention, Figure 1 is a plan view of the machine. Fig. 1^a is a plan view of guides detached. Fig. 2 is a side elevation of the machine with parts removed. Fig. 3 is a similar view looking toward the other side of the machine. Fig. 4 is an end view partly in section and with parts omitted. Fig. 5 is an enlarged plan view of cigarette-rod-forming devices. Fig. 5^a is a detail plan view. Fig. 6 is a section on line 6 6, Fig. 5. Fig. 7 is a detail sectional view on plane of line 7 7, Fig. 6. Fig. 8 is a detail sectional view on plane of line 8 8, Fig. 6. Fig. 9 is a detail sectional view on plane of line 9 9, Fig. 6. Fig. 10 is a section on line 10 10, Fig. 5^a. Fig. 11 is a section on line 11 11, Fig. 5^a. Fig. 12 is a section on line 12 12, Fig. 5^a. Fig. 13 is a detail sectional view on plane of line 13 13, Fig. 6. Fig. 13^a is a detail sectional view on plane of line 14 14, Fig. 6. Fig. 13^b is the same as Fig. 13^a, showing the parts operating in a slightly - different manner. Fig. 14 is an end elevation, partly in section, of the pasting device. Fig. 15 is a longitudinal vertical section of the same, partly in elevation and with some parts omitted. Fig. 16 is a view showing a plan of the bed-plate of the pasting device and the manner in which the various moving parts are driven. Fig. 17 is a detail view of a detached part. Fig. 18 is an alternative construction of a portion of the tobacco-rod-forming device.

Referring to the drawings by reference characters, A represents the main frame of the machine, having bolted thereto and extending at

right angles therefrom a supplemental frame A', in which is mounted a tobacco - feeding mechanism A². This mechanism may be of any desired construction and forms no part of this invention. Any device by which tobacco may be well disintegrated and separated and the tobacco fibers delivered therefrom in a constant and uniform shower may be employed. In my application filed December 11, 1897, Serial No. 661,478, for a cigarette-machine, I show and describe a feeding mechanism which I find in practice to be highly efficient, and for the purpose of illustration a similar device is indicated in operative connection with the present machine.

The discharge-spout A¹⁰ of the feeder is preferably provided with a rather long and narrow outlet A³, located directly over a longitudinal groove or channel B' in the bracket 20 B. This bracket is bolted to the main frame of the machine and extends from end to end thereof in a direction at right angles to the feeding device, and the groove B' is formed, preferably, by one or more sets of elongated 25 guide-pieces disposed in parallel pairs and suitably secured to bracket B. The drawings show two distinct sets of such guide-pieces a a and b b, the former placed rather wide apart and forming a channel rectangular in cross- 30 section and the latter placed relatively near together. A continuation of the channel B' is formed between the guide-pieces c c, which, together with the grooved bottom plate C', form a channel whose sides are parallel or 35 nearly parallel and whose bottom is uniformly semicircular.

The vertical walls of the guides a a are undercut, or, in other words, are provided with slits or kerfs a' a', which are flush with the 40 bottom of channel B' and which extend into said walls in a direction at right angles thereto. The walls b b are also undercut or recessed in a manner to be described hereinafter.

45 The two sets of guides a a and b b are spaced apart, as shown, and the intervening space is occupied by the two similar horizontal disks E E. These disks are mounted on vertical spindles e e, located one on each side 50 of said channel B' and are adapted to rotate in rather close proximity to the bracket B. The peripheries of said disks are preferably flat, and the space between them at the point where they come nearest together is equal 55 to or somewhat less than the space between guides b b.

G is a small roller carried upon an arm g², pivoted to the standard g³, and G² is a large roller mounted upon a shaft g⁴, also mounted 60 on said standard. A nut g⁸ is adapted to hold arm g² rigid. By loosening said nut the roller G may be turned up out of the way whenever access to the channel B' at this point is desired. The shaft g⁴ also carries 65 thereon spiral gear-wheels g⁹ g⁹, which engage similar wheels g¹⁰ g¹⁰, mounted one upon each of the spindles e e. An endless belt F

is adapted to travel over the two rollers aforesaid, shaft g⁴ being driven by shaft g⁵ through spiral gear-wheels g⁶ and g⁷.

K is a vertical disk having, preferably, a grooved periphery and mounted in such manner as to project into the channel B' between the guides b b. The shaft of the disk carries a beveled gear-wheel k, which engages a similar wheel k' on the shaft k². A spiral gear-wheel k³, also mounted on shaft k², engages wheel g⁷, before mentioned.

P is a tongue or bridge piece composed, preferably, of a length of thin metal concaved on the under side thereof and mounted on a bracket p in such manner as to project into the channel B' between the guides b b, a narrow clear space being left between each side of the tongue or bridge piece and the adjacent wall of the said guides, as shown in Figs. 1, 5, and 9. One end of the tongue is located close to and substantially tangent to the bottom of the groove in the disk K, the other end thereof being closely adjacent the first 90 plate R of the wrapper - folding device, as best shown in Figs. 1 and 5.

A⁵ represents the main driving-shaft of the machine, and A⁶ the pulley by which the same is driven from any suitable source of power. 95 The shaft A⁵ extends from end to end of the frame A and is mounted in bearings a⁴ a⁴. A pulley a⁵ is mounted on a short transverse shaft a⁶, which is driven by shaft a⁸ through bevel-gears a⁷, the shaft a⁸ being connected 100 with the main shaft A⁵ by the spur-gears a⁹. Shaft a⁸ also carries a spiral gear-wheel a¹⁰, which engages a similar wheel a¹¹ on the lower end of shaft g⁵ aforesaid. Pulley a⁵ is the driving medium for the endless tape or band 105 d, to which the paper wrapper-strip d' is applied. The course of the tape d is as follows, reference being had particularly to Fig. 3: Starting from point marked x the tape d passes upwardly and over roller d², thence to guide- 110 roller d³ through the guiding-bracket d⁴, which is for the purpose of centering the tape at 115 this point. From roller d³ the tape passes between guides a a, its edges projecting into the kerfs a' a', thence under disks E E to guides 120 b b, where the edges of said tape are caused to turn up and conform to the peculiar formation of said guides b' b'. Passing disk K it enters that part of channel B' between guides c c in the shape of a trough, whose sides are 125 parallel and whose bottom is semicircular. Then it passes through the folder formed by plates R and R' substantially in the shape of a hollow cylinder. Emerging from the folder the tape d resumes its flat condition and passes 130 over roller d⁶ to guide-roller d⁷. Passing between roller d⁸ and pulley a⁵ it makes about three-quarters of a turn about said pulley and then passes between said pulley and roller d⁹ to point x. Roller d⁹ is carried by a pivoted arm 135 d¹⁰, which is adapted to swing in an arc intersecting the periphery of the pulley a⁵, and under the influence of the traveling tape d it is caused to bind said tape tightly against the

periphery of pulley a^5 to prevent slip between the two. The roller d^9 is also carried by a pivoted arm d^{11} , which, however, swings free of the pulley a^5 . Its purpose is, with the aid of spring d^{12} , to take up slack in tape d , due to stretching or other causes, and to assist roller d^8 in preventing slip by exerting at all times a pull upon said tape in a direction tending to bind the same tightly against the periphery of 5 said pulley. The function of the tape, as before mentioned, is to convey the wrapper-strip (with its contained charge of tobacco) through the shaping and compressing devices above referred to. The wrapper d' , which is somewhat wider than the tape, is led from the reel D through the guide d^{13} , by which it is properly adjusted with respect to tape d , and then lying closely against the outer surface of said tape, with one edge overlapping the same, it 10 enters the groove or channel B', between the guide-pieces $a a'$, the edges of the paper extending into and fitting the slits or kerfs $a' a'$, before mentioned. Passing beneath the spout A¹⁰ the wrapper-strip d' receives a rather 15 thick layer of tobacco fibers, which, it should be assumed, are falling in a constant and uniform shower from the tobacco-feeder A², before referred to. An adjustable vertical roller G', located just beyond the spout A¹⁰ and 20 suitably driven, is mounted at such an elevation that the tobacco, which approaches said roller in a loose flaky but rather bulky mass, is suddenly compressed as it passes under the same. The tobacco expands somewhat as 25 it is carried beyond roller G, but is again compressed on reaching belt F. Belt F passes from roller G² across the upper faces of disks E E, as shown in Fig. 6, to roller G in a substantially-straightline, although a slight drop 30 toward roller G is advantageous and serves to retain the tobacco in its compressed condition and assist the tape d in further advancing the same. Passing between disks E E the tobacco is compressed in a lateral direction, 35 and from this point until it passes from under the roller G it retains the form of a substantially-rectangular rod, closely confined between the paper wrapper at the bottom, the endless belt at the top, and the rollers E E 40 and the guides $b b$ at the sides. 45 For the greater part of the above-described operation the wrapper-strip remains perfectly flat, but on reaching the guides $b b$ it begins to curl or rise at its edges and form itself into trough-like shape, the curve of the "trough" being slight at first, but becoming more and more marked as the disk K is approached. This of course is due to the operation of the folding device hereinafter described, the result 50 of forming the wrapper-strip into a cylinder being felt with gradually-diminishing effect along a considerable length of the paper strip. The ends of the guides $b b$ adjacent the disks E E are undercut in a manner 55 similar to that of guides $a a'$, so that the paper at this point—that is, at the beginning of said guides $b b$ —may be flat. Beyond said

point the guides are cut away in such manner as to admit of the gradual rise of the edges of the paper, as above referred to; a depending wall or flange b^3 being retained between said edges and the tobacco rod. This depending wall or flange affords a sort of guide and support b^4 for the paper and serves to keep the same from wrinkling or tearing 70 as it gradually assumes its trough-like shape. Having passed under roller G, the tobacco is permitted to expand in a vertical direction before being acted upon by the disk K. Up to this stage of the operation the tobacco has 80 become rounded only on the under side thereof, but on reaching the said disk K it is compressed into the form of a complete cylinder, while the wrapper is caused to assume the shape of a trough whose sides are parallel and 85 whose bottom is semicircular in cross-section. The tongue P serves to retain the cylindrical shape of the tobacco as it is carried on to the folder. The wrapper is now ready to be supplied with paste and folded down over the 90 tobacco rod. 95 Any suitable mechanism by which the wrapper-strip may be folded around the tobacco rod and any suitable mechanism for supplying paste to the wrapper or providing other means for permanently securing the same in folded position may be used in conjunction with the devices already described. One embodiment of my improved folder is shown in Figs. 1, 5, 13, and 13^a. It consists of the two 100 similar plates R and R', placed one after the other and bolted one on either side of the channel B'. Plate R, as shown, is secured to one side of the channel B' and extends across the same nearly to the opposite wall thereof, 105 a narrow space being left between said wall and the outer edge of said plate. Plate R' in this embodiment of my invention may be substantially the same as plate R, except that its position relative to channel B' should be 110 reversed. Those portions r^2 and r^3 of plates R and R' that lie directly over channel B' are concaved on their under sides, as clearly shown in Figs. 13 and 13^a. 115

In the operation of the folder the upstanding sides or edges of the wrapper strip or trough are folded down one at a time. Preferably that side or edge of said wrapper strip or trough which overlaps the corresponding edge of tape d is folded down first. This 120 folding is accomplished by plate R, which acts in a manner similar to that of a hemmer on a sewing-machine, so that the aforesaid side or edge of the wrapper-strip as it passes under said plate is laid smoothly over the tobacco rod, while the other or upstanding side or edge of said wrapper strip or trough passes through the narrow space between wall c and the extreme outer edge r^3 of plate R receives 125 a supply of paste. Referring to Fig. 13, the relative positions of tobacco rod and the two sides of the wrapper-trough as the same pass plate R will be clearly seen. This figure also shows in dotted lines a thin wheel or disk 130

T^5 , which, as will hereinafter appear, is adapted to rotate in contact with the aforesaid upstanding side or edge of the wrapper strip or trough d' and deliver a film of paste thereto.

5 When this paste is applied, it is obvious that the strip will be moistened, because the paste is more or less wet, and therefore the pasting mechanism is also a moistening device. Passing on to plate R' , which operates similarly to plate R , the upstanding edge is also folded down, and owing to the fact that the tape is narrower than the paper and does not extend to the edge of the first-mentioned fold the two edges of the paper are brought together 10 and a permanent joint effected. Should a tape be used of the same or greater width than the paper, the joint might be made by the same folder by simply causing that edge of the tape which was first turned down by 15 plate R to pass outside of the edge r^3 of plate R' instead of undersaid plate. This is shown in Fig. 13^b. Emerging from the folder the now-completed cigarette-rod passes on to the cutter, the part h being merely a guide which 20 may or may not be used; but before explaining the cutter I will describe in detail my improved pasting mechanism, with particular reference to Figs. 1, 2, 14, 15, 16, and 17.

T is a cylinder containing a suitable paste, 25 and t a piston therefor, carried on the end of the screw-threaded rod t' . The rod is surrounded by an internally-threaded sleeve or nut T^2 , which is mounted in a part of the supporting-frame T' and while free to rotate 30 is held against longitudinal movement by the collars T^8 and T^9 . The collar T^9 is provided with an annular surface having ratchet-teeth 35 cut therein, and a pawl 3 , carried by an arm 4 , mounted concentrically with the axis of the rod t' , engages the same, a spring 15 holding said pawl in engagement with said teeth. A stud 5 , carried by a disk or crank 6 , projects into a slot 7 in the outer end of said arm. The disk is fixed to one end of a shaft 40 45 50 55 60 65 70 75 80 85 90 95 100 105 110 115 120 125 130 135 140 145 150 155 160 165 170 175 180 185 190 195 200 205 210 215 220 225 230 235 240 245 250 9805 9810 9815 9820 9825 9830 9835 9840 9845 9850 9855 9860 9865 9870 9875 9880 9885 9890 9895 9900 9905 9910 9915 9920 9925 9930 9935 9940 9945 9950 9955 9960 9965 9970 9975 9980 9985 9990 9995 9999

contact with the upstanding edge of the wrapper-trough, as hereinbefore described. The upper end of said vertical shaft T^{10} carries a horizontal pulley 17 and a swinging arm T^6 , upon which are mounted the two vertically-disposed guiding sheaves or pulleys 18 and 19. An endless belt 21, running from driving-pulley 22 on the main shaft A^5 , passes over pulley 19, thence horizontally around pulley 17, over pulley 18, and back to pulley 22.

The rubbing contact between roller T^4 and spout T^8 causes a film of paste to be spread evenly over the surface of the periphery of said roller, and as the disk T^5 , to which said paste is transferred, also rotates, but in a plane at right angles to roller T^4 , the paste is still more evenly distributed and smoothed out before being applied to the cigarette-wrapper. The rollers m are intended to hold the paper up to the disk T^5 .

It will be noticed that the above-described parts are all mounted upon a common base or bed-plate, hereinbefore referred to as "frame T' ." A shank or spindle T^7 , forming a depending portion of said frame, extends into the socket T^8 , fixed to the main frame A , and rests upon the end of an adjusting-screw 23. Thus by loosening set-screw 25 the whole above-described organization may be turned bodily in the socket T^8 and the disk T^5 moved toward or from the aforesaid wrapper-folding device, or it may be raised and lowered and maintained at any desired height therein by manipulating the screw 23 and set-nut 24.

It is obvious that many changes may be made in the construction herein disclosed without departing from the spirit of my invention. I therefore do not desire to limit myself to the embodiment herein disclosed.

I claim—

1. In a cigarette-machine in combination, a portion having a groove, means to feed a continuous strip of paper to said groove, a feeder to deliver loose tobacco in a continuous supply upon said paper, means to form a continuous rod of said tobacco and move the same and said paper along said groove, a curved compressor for the exposed portion of the rod within said groove and means to at the same time fold one edge of said paper over said compressor.
2. In a cigarette-machine in combination, a portion having a groove, means to feed a continuous strip of paper to said groove, a feeder to deliver loose tobacco in a continuous supply upon said paper, means to form a continuous rod of said tobacco and move the same and said paper along said groove, a curved compressor for the exposed portion of the rod within said groove and means to at the same time fold one edge of said paper over said rod.
3. In a cigarette-machine in combination,

- means to feed a continuous strip of wrapping material in a substantially-flat condition, means to feed loose tobacco onto said strip whereby the same is carried along with said strip, a pair of flat-faced wheels on opposite sides of said tobacco to compress the same while moving along with said strip, a belt also moved along with said strip, and located on the other side of said tobacco to prevent the tobacco from escaping, whereby a substantially-square rod is formed and means to act directly upon and further compress said rod into substantially the shape of the compressed cigarette while moving along in contact with said strip, means to moisten one edge of said strip and fold the opposite edge of said strip over and down upon said rod, the two edges overlapping.
4. In a cigarette-machine in combination, a table, a belt moving along said table and presenting a substantially-flat surface, means to feed a strip of wrapping material onto said belt and move the same along with said belt in substantially-flat condition, means to feed tobacco upon said strip of wrapping material, means to compress said tobacco down upon said strip as the same is moving, a pair of substantially flat-faced rollers located on opposite sides of said tobacco and moving to compress the same from each side and there-
- by form a substantially-square rod, means to compress the same into a round rod as the same is moving along in contact with said strip and means to fold the opposite edges of said strip over and down upon said rod, the edges thereof overlapping whereby a continuous cigarette is formed.
5. In a cigarette-machine in combination, a table, means to feed a continuous strip of wrapping material in a substantially-flat condition along said table, means to feed loose tobacco onto said strip whereby the same is carried along with said strip, a pair of flat-faced wheels on opposite sides of said tobacco to compress the same while moving along with said strip, a belt also moved along with said strip and located on the other side of said tobacco to prevent the tobacco from escaping, and means to further compress said rod into substantially the shape of the completed cigarette while moving along in contact with said strip and without folding said wrapper over said rod, means to moisten one edge of said strip and fold the opposite edges thereof over and down upon said rod, the two edges overlapping.
